COMB

Edwal A. Stone, Kansas City, Mo., assignor to
O. M. Franklin Serum Company, Denver, Colo.,
a corporation of Colorado

Application April 1, 1938, Serial No. 199,458

3 Claims. (Cl. 119—86)

This invention relates to improvements in combs and has reference more particularly to combs of the type usually called "Scotch combs".

Breeders of fancy livestock and especially of stock destined for show purposes find it necessary to carefully curry and comb such animals in order to keep the hair in the best possible condition and appearance.

Many animals have long hair and an ordinary curry comb is not suitable for obtaining the best results and in such cases combs with long teeth are employed. Some combs for this purpose are made of metal and have a handle projecting from one side, such combs are generally called "Scotch combs".

The comb that forms the subject of this invention is of the "Scotch" type and is usually provided with a handle, the improvement, however, may be used whether a handle is used or not.

It is the object of this invention to produce a comb of substantial construction that can be readily made from metal and which will have round teeth instead of the ordinary rectangular teeth usually employed with metal combs.

Another object is to produce a comb in which the body and the teeth assembly can be manufactured independently and attached together at any time thereafter.

A further object is to produce a teeth assembly that can be manufactured in long strips that can be cut into sections of any desired length and attached to the comb body.

A still further object is to produce a metal comb body formed from two identical members that can be assembled to form a body having one side provided with a longitudinal recess for the reception of a section of teeth assembly that can be inserted in the recess and sweated in place.

The above and any other objects that may become apparent as this description proceeds are attained by means of a construction and an arrangement of parts that will now be described in detail and for this purpose reference will be had to the accompanying drawing in which the invention has been illustrated and in which:

Figure 1 is a top plan view of the comb;

Figure 2 is a section taken on line 2—2 Fig. 1;

Figure 3 is a section taken on line 3—3 Fig. 2;

Figure 4 is a section taken on line 4—4 Fig. 2;

50 and

Figure 5 is a side view of a portion of the teeth assembly.

In the drawing reference numeral 6 designates the comb body and 7 the teeth while reference numeral 8 designates the handle which is con-

nected to the comb body by two divergent bars 9 that are riveted to the comb body as indicated by reference numeral 10.

The comb body is formed from two identical members 11 secured back to back by spot welding 12 or by rivets. Each member 11 has a strengthening rib 13 and guard teeth 14. The inner edges of members 11, along the bottom of the guard teeth 14 are pressed outwardly in the manner indicated by 15 so as to provide a channel for the 10 teeth assembly which will now be described.

The teeth are assembled separately from the comb body and the assembly is formed from the narrow strips 16 of corrugated metal. The teeth are round, needle like members having one end 15 tapered. The teeth are laid in adjacent depressions in one strip 16 and a second strip is then placed over them and the assembly soldered. Suitable forms or templets may be used to facilitate the assembly and the strips may be made as long as desired. When a comb is to be made the base members 11 are first assembled and spot welded or riveted together. A teeth strip is now cut of the proper length to fit the recess between sides 15 after which the comb is placed with the teeth uppermost between heating elements and solder applied in such a way that it will fill the spaces between the strips 16 and sides 15. Some of the solder will flow into the space between members 11, thereby forming a sweated assembly 20 25 30 that is almost as solid as if it were made from a single piece. The teeth may be secured in place either before or after the comb is attached to rods 9.

It will be observed from Fig. 3 that rods 9 are 35 provided with integral shoulders that engage one side of the body while the riveted head engages the other and this serves to hold the two parts 11 in assembled position during spot welding and soldering.

40 By employing the construction described, round teeth of steel or other metal can be used which do not cut or injure the hair. The sharp round teeth penetrate very easily the heaviest coats of hair or fur and give the animal's coat a smooth 45 glossy finish that greatly enhances its natural beauty.

Attention is called to the fact that the two plates 11 may be duplicates and therefore require but one die, and the same is true for strips 16.

The comb, constructed as shown and described, is strong and effective and can be easily manufactured.

Having described the invention what is claimed as new is:

- 5 1. A comb having a body formed from two separate pieces having a guard tooth at each end, the edge of each piece being pressed outwardly between the inner edge of the guard teeth, the outwardly pressed portions complementing each other to form an elongated recess having a bottom and end walls, the two pieces having each 10 two identically spaced openings, handle bars passing through the openings, the bars having integral shoulders for engaging one side of the body, the ends of the bars being riveted to engage the other side, the handle bars serving to hold the two pieces in cooperating position and a teeth assembly positioned in the recess and attached to the walls of the recess by solder.
- 15 2. A comb having a body formed from two separate pieces having a guard tooth at each end, the edge of each piece being pressed outwardly between the inner edge of the guard teeth, the outwardly pressed portions complementing each 20

other to form an elongated recess having a bottom and end walls, each piece having a rib pressed outwardly and positioned parallel with the bottom of the recess and spaced from the bottom wall of the recess, the pieces having two holes positioned between the bottom wall of the recess and the rib for the reception of securing rivets, rivets in said openings and a teeth assembly in the recess, secured to the walls of the recess by solder. 5

3. A comb having a frame formed of two separate pieces each having a U-shape and provided with a recess between the arms of the U, means for positioning the two pieces and securing them to each other with the recesses oppositely arranged to form an elongated opening, a series of 10 comb teeth, transversely corrugated strips receiving comb teeth in the corrugations thereof, said strips being positioned within the opening, and means comprising solder for securing the teeth and strips within the opening. 15
